[57] CLAIM

The ornamental design for a compact disc pack, as shown and described.

DESCRIPTION

FIG. 1 is a perspective view of a compact disc pack in its open condition showing my design and, in particular, showing the configuration of the cut-out in which the compact disc can be inserted;

FIG. 2 is a perspective view, shown in a closed condition;

FIG. 3 is a front elevational view thereof;

FIG. 4 is a top plan view thereof;

FIG. 5 is a bottom plan view thereof;

FIG. 6 is a rear elevational view thereof;

FIG. 7 is a side elevational view thereof; and,

FIG. 8 is an opposite side elevational view.
